UNITED STATES PATENT OFFICE.

GUSTAVE E. VILLARET, OF LEONIA, NEW JERSEY, ASSIGNOR TO METROPOLITAN-COLUMBIA MFG. CO., INC., A CORPORATION OF NEW YORK.

DESIGN FOR A LIGHTING-FIXTURE STRAP OR ARTICLE OF ANALOGOUS NATURE.

Application filed February 25, 1928. Serial No. 25,592. Term of patent 3½ years.

To all whom it may concern:

Be it known that I, GUSTAVE E. VILLARET, a citizen of the United States of America, and a resident of Leonia, county of Bergen, and State of New Jersey, have invented a new, original, and ornamental Design for a Lighting-Fixture Strap or Article of Analogous Nature, of which the following is a specification, reference being had to the accompanying drawing, forming a part hereof.

In the drawing:

Figure 1 is a front elevational view of the lighting fixture strap or article of analogous nature;

Figure 2 is a diagrammatic side elevational view of the same; and

Figure 3 is a sectional view on the line 3—3 of Figure 1.

I claim:

The ornamental design for a lighting fixture strap or article of analogous nature substantially as shown.

GUSTAVE E. VILLARET.
